DESIGN.

S. M. ISRAEL.

COMBINATION LAMP STAND AND SMOKING SET.

APPLICATION FILED NOV. 19, 1920.

58,028.

Patented May 31, 1921.

Inventor:
Sidney M. Israel,
By his Attorney Leo F. Mait

UNITED STATES PATENT OFFICE.

SIDNEY M. ISRAEL, OF RICHMOND HILL, NEW YORK.

DESIGN FOR A COMBINATION LAMP-STAND AND SMOKING SET.

58,028.

Specification for Design.

Patented May 31, 1921.

Application filed November 19, 1920. Serial No. 425,282. Term of patent 7 years.

To all whom it may concern:

Be it known that I, SIDNEY M. ISRAEL, a citizen of the United States, residing at Richmond Hill, county of Queens, and State of New York, have invented a new, original, and ornamental Design for a Combination Lamp-Stand and Smoking Set, of which the following is a specification, reference being had to the accompanying drawing, forming part thereof.

The figure is a perspective view of a smoker's electric lamp post, showing my new design.

I claim:

The ornamental design for a combination lamp stand and smoking set as shown.

SIDNEY M. ISRAEL.
